UNITED STATES PATENT OFFICE

2,496,698

WINDOW LOCK

Roy C. Chapman, Detroit, Mich.

Application July 19, 1946, Serial No. 684,717

5 Claims. (Cl. 292—210)

1

This invention relates to window locks, and more particularly to a device for locking a window in a partly opened position.

A main object of the invention is to provide a novel and improved window sash lock device of very simple construction which is very easy to install and operate.

A further object of the invention is to provide an improved window sash lock device which is inexpensive to manufacture and is very efficient in operation, said lock device comprising only a few simple parts and which can not readily get out of order.

Further objects and advantages of the invention will become apparent from the following description and claims, and from the accompanying drawings, wherein:

Figure 1 is a front elevational view of a portion of a window equipped with a window sash lock device according to the present invention.

Figure 2 is an elevational view of the upper lock member of the window sash locking device employed in Figure 1.

Figure 3 is a horizontal cross sectional view taken on line 3—3 of Figure 2.

Figure 4 is a top plan view of the lower lock member employed in the sash locking device of Figure 1, showing in dotted lines the latch when closed in order to engage the lug of the upper sash lock.

Figure 5 is a front elevational view of the lower lock member of Figure 4.

Figure 6 shows a side view in elevation of the upper lock member in locking position, and in dotted lines the position of the arm and lug when in inactive position.

Referring to the drawings, 11 designates the upper sash and 12 designates the lower sash of a conventional double-sash window structure. It is frequently desired to lock the lower sash in a partly raised position wherein it provides ventilation but does not permit entry of unauthorized persons. According to the present invention, a locking means is provided comprising an upper lock member 13 secured to the side frame portion of sash 11, and a lower lock member 14 secured to the top of lower sash 12 and lockingly co-operating with upper member 13. Upper lock member 13 comprises a plate member 15 carrying at one side thereof a box-like housing 16. Housing 16 has upper and lower securing tabs 17 and 18 for securing of the lock member to the inner side surface of the sash side frame member in the position shown in Figure 1. Plate member 15 is also secured to

2

the side frame member at its front surface by a wood screw 19 or the like. Rotatively secured in housing 16 is a laterally projecting shaft member 20 formed with a depending arm 21 having a forwardly projecting lug 22 at its lower end. Shaft member 20 is resiliently secured inside housing 16 by a coil spring 23 which encircles the shaft member and bears between the inner wall surface of the housing and a removable split washer 24 secured to the inner end portion of the shaft member. Coil spring 23 is under compression between the housing 16 and the split-washer 24 so that the end of the arm 20 is pressed inwardly where it engages with the window frame 11, to form a frictional detent in any position, either upwardly extended to the position indicated in dotted lines in Figure 6, where the arm is totally within the space between the glass of the upper frame 11 and the rail of the lower frame 12, or in the lower and locking position shown in full lines in that figure, where it is selectively engaged by its lug 22 with the lower latching member 28 or is positioned above member 28, so that the window may be raised a certain distance only.

Lower lock member 14 comprises a horizontal bracket member 25 having depending legs 26, 26' formed with laterally extending lugs 27, 27' for securing the bracket member to the top of the lower sash 12. Pivottally secured to bracket member 25 is a latch arm 28 formed with an upstanding handle 29. As shown in Figure 1, latch arm 28 may be swung to overlie lug 22 of the upper lock member 13 to thereby secure lower sash 12 against either upward or downward movement with respect to upper sash 11, downward movement being resisted by the abutment of latch arm 28 with lug 22 and upward movement being resisted by the abutment of lug 22 with the top of lower sash 12. To release the lock members, latch arm 28 is swung outwardly to the full line position thereof shown in Figure 4.

While a specific embodiment of a sash locking device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. Sash locking means for windows of the type having an upper sash and a lower sash slideable with respect to said upper sash, comprising a

plate member adapted to be secured to a side frame element of the upper sash, a housing carried at one side of said plate member, an arm pivotally mounted in said housing for rotation around a horizontal axis, a forwardly projecting lug carried by said arm, a horizontal bracket adapted to be secured to the top of the lower sash adjacent said arm, and a latch member pivotally secured to said bracket for rotation in a horizontal plane, said latch member being formed and arranged to overlie said lug.

2. Sash locking means for windows of the type having an upper sash and a lower sash slidable with respect to said upper sash, comprising a plate member adapted to be secured to a side frame element of the upper sash, a housing carried at the inner side of said plate member, a horizontal shaft journalled in said housing, a depending arm carried by said shaft, a forwardly projecting lug on said depending arm, a horizontal bracket, means securing said bracket to the top of the lower sash in vertically spaced position above said top, and a horizontal latch member pivotally secured to said bracket, said latch member being formed and arranged to overlie said lug, said lug being formed to overlie the top of the lower sash, whereby movement of the lower sash with respect to the upper sash is restrained.

3. Sash locking means for windows of the type having an upper sash and a lower sash slidable with respect to said upper sash, comprising a plate member secured to a side frame element of the upper sash, a box-like housing carried at the inner side of said plate member, a horizontal shaft journalled in said housing, means exerting frictional pressure on said shaft to prevent free rotation thereof, a depending arm carried by said shaft, a forwardly projecting lug on the end of said depending arm, said lug being formed to overlie the top of the lower sash, a horizontal bracket member, means securing said bracket member to and in raised position above the top of said lower sash, and a horizontal latch member pivotally secured to said bracket member, said latch member being formed and arranged to overlie said lug.

4. Sash locking means for windows of the type

having an upper sash and a lower sash slidable with respect to said upper sash, comprising a plate member secured to a side frame element of the upper sash, a box-like housing carried at the inner side edge of said plate member inwardly of said frame element, a horizontal shaft journalled in the side wall of said housing, spring means in said housing exerting frictional pressure on said shaft to prevent free rotation thereof, a depending arm carried at the outer end of said shaft, a forwardly projecting lug on the end of said depending arm, said lug extending forwardly over the top of the lower sash, a horizontal bracket member, means securing said bracket member to the top of said lower sash in vertically spaced relation thereabove, and a horizontal latch member pivotally secured to the top surface of said bracket member, said latch member being formed and arranged to overlie said lug.

5. Sash locking means for windows having an upper sash and a lower sash slidable with respect to said upper sash comprising a housing adapted to be secured to the upper sash within the frame area free of conflict with the lower sash in raised position, a shaft journalled in said housing, a spring biasing said shaft in said housing to provide a frictional fit between one end of said shaft and said upper sash, an outwardly extending lug on the other end of said shaft, and a pivotally secured latch member on the lower sash adapted to engage said lug on said shaft in one of two positions, whereby said upper and lower sashes may be secured with said lug and latch in one position and may be movable within limits with said lug and latch in the other position.
